(57) **CLAIM**

The ornamental design for a dresser drawer with pockets, as shown and described.

DESCRIPTION

FIG. 1 is a front elevation of my dresser drawer with pockets;

FIG. 2 is a side elevation as viewed from one side of my dresser drawer with pockets;

FIG. 3 is a side elevation of my dresser drawer with pockets as viewed from an opposite of the dresser drawer with pockets shown in FIG. 1;

FIG. 4 is a top plan view of my dresser drawer with pockets;

FIG. 5 is a bottom plan view of my dresser drawer with pockets;

FIG. 6 is a rear view of my dresser drawer with pockets as shown in FIG. 1; and,

FIG. 7 is an enlarged fragmentary perspective view of my dresser drawer with pockets only with one of the drawers shown in an open position with the pocket being shown in an elevated position when removed from the dresser drawer with pockets.

The details shown in broken lines are for illustrative purposes only and form no part of the claimed design.
